UNITED STATES PATENT OFFICE

2,594,878

HANDLE CONNECTION

Clarence L. Davis, St. Louis, Mo.

Application August 18, 1948, Serial No. 44,899

1 Claim. (Cl. 306—44)

1

The present invention relates generally to holding devices, and more particularly to a readily releasable handle construction finding particular adaptation to solder paddles, reversible files, and the like.

An object of the present invention is to provide a novel releasable handle construction and its adaptation to solder paddles, reversible files, and the like.

Another object is to provide a novel releasable handle construction which is firmly anchored to the working portion of the device to which it is applied when in operating position in respect thereto in a manner substantially eliminating relative lateral movement.

Other objects are to provide a novel handle construction for solder paddles, and the like, which is readily and easily applied and removed, which is inexpensive to make, which is adapted to render long service without requiring any maintenance, and which may be applied to and removed from a working member with minimum instruction.

The foregoing and other objects and advantages are apparent from the following description taken with the accompanying drawing, in which:

Fig. 1 is a plan view of a handle construction formed in accordance with the teachings of the present invention applied to a solder paddle;

Fig. 2 is a side elevational view thereof;

Fig. 3 is an enlarged vertical transverse cross-sectional view on the line 3—3 of Fig. 2, portions being shown in end elevation;

Fig. 4 is an enlarged fragmentary longitudinal vertical cross-sectional view taken on substantially the line 4—4 of Fig. 1;

Fig. 5 is an enlarged transverse vertical cross-sectional view on substantially the line 5—5 of Fig. 1;

Fig. 6 is an enlarged fragmentary plan view of the recessed portion of the solder paddle which receives the handle construction;

Fig. 7 is an end view of the solder paddle looking towards the open end of the handle construction receiving recess; and

Fig. 8 is a fragmentary enlarged longitudinal vertical cross-sectional view through the attaching end of the handle construction, the hinged clamping or jaw member being shown in released position.

Referring to the drawing more particularly by reference numerals, 10 indicates generally a solder paddle incorporating a handle construction 12 and a paddle or work member 14 including the concepts of the present invention.

The handle construction 12 includes an attaching flat-bottom base member 16, formed integral with which is a hand-grip supporting arm 18 to which is secured a hand-grip member 20,

2

preferably of wood, by suitable screws 22. The hand-grip supporting arm 18 includes an arcuate neck portion 24 formed on an arc of ninety degrees so that the hand-grip member 20 is disposed in an offset plane parallel with the work member 14.

The attaching base member 16 includes an integral depending transverse flange or stationary jaw 26 which forms an acute angle with the bottom 28 of the member 16. Also formed integral with the member 16 is a longitudinally extending boss 30 having a threaded longitudinally extending well 32 which receives a suitable screw 34 having a knurled head. A movable jaw member 36 is pivotally mounted on a pin 38 supported by a central hinge sleeve 40 formed integral with the arcuate neck portion 24. The jaw member 36 includes spaced integral hinge sleeves 42 between which is disposed the hinge sleeve 40. The movable member 36 also includes an integral flange 44 which is at substantially ninety degrees thereto. Between the flange 44 and its hinge connection, the movable member 36 includes a slot 46 through which the screw 34 extends. It is manifest that the flange 44 is in opposed relation with the flange 26.

The work member 14 has a longitudinal recess 48 in the upper surface adjacent one end (Figs. 6 and 7). The recess 48 is of shallow depth and is defined by side walls 50. A transverse channel 52 is formed at the inner end of the recess 48 and extends into the body of the work member 14 at an acute angle to the surface of the recess 48. Extending beneath the recess 48 from the end of the work member 14 is a channel 54.

In Fig. 4 the relationship of the handle construction 12 and the work member 14 is clearly illustrated. The base member 16 fits into the recess 48 with the flange 26 extending into the channel 52. The flange 44 of the movable member 36 extends into the channel 54 and is securely maintained in position by the screw 34, the head of which bears against the movable member 36. Both the snug fit of the base member 16 in the recess 48 between the walls 50 and the clamping engagement of the flanges 26 and 44 in their respective channels 52 and 54 insures a rigid connection between the handle construction 12 and the work member 14.

Manifestly, the handle construction 12 may be quickly removed from the work member 14 by loosening the screw 34 and pivoting the movable jaw member 36 rearwardly to some such position as that shown in Fig. 8, whereupon the flange 26 may be removed from the channel 52.

As has been pointed out above, the present handle construction 12 finds particular adaptation to a solder paddle, the work member of which is normally of wood which becomes burned in its use and requires replacement at relatively

frequent intervals. Another application is a flat file of the type which employs an offset handle. Manifestly, the handle construction is adapted for other uses.

It is apparent that there has been provided a handle construction and a particular adaptation which fulfill the objects and advantages sought therefor.

It is to be understood that the foregoing description and the accompanying drawing have been given by way of illustration and example. It is also to be understood that changes in form of the elements, rearrangement of parts, and substitution of equivalent elements, which will be obvious to those skilled in the art, are contemplated as within the scope of the present invention which is limited only by the claim which follows.

What is claimed is:

A work tool comprising, in combination, an expendable paddle-like work member, such as a trowel, spatula, or the like, which must be supported from a rearward end for proper use thereof, a longitudinal recess in said work member extending forwardly from said rearward end, said recess having a horizontal plane surface and parallel vertical sides, a first transverse channel formed at the forward end of said recess and extending downwardly and rearwardly therefrom, a second transverse channel formed at the rearward end of said work member and extending horizontally forwardly therefrom, a handle construction releasably secured to said work member including a base having a lower horizontal plane surface and parallel vertical sides snugly disposed in said recess thereby eliminating relative lateral

movement between said work member and said handle construction, said base including a transverse hook portion extending downwardly and rearwardly from a forwardly disposed end thereof, said hook portion engaging a wall of said first transverse channel in said work member, a handle grip support extending upwardly and rearwardly from said base, a member pivotally connected to said grip support, said pivotally mounted member having a transversely extending flange releasably engaging a wall of said second channel in said work member, and a screw extending through said pivotally mounted member and anchored in said base for drawing pivotally mounted member into position engaging a wall of said second channel to secure said handle construction on said work member.
